By Frank H. Marks, G.M.

UNITED STATES PATENT OFFICE

118,116

DESIGN FOR A PIANO

Henry R. Heller, New York, N. Y., assignor to Winter & Co., New York, N. Y., a corporation of New York

Application February 19, 1938, Serial No. 75,287

Term of patent 3½ years

To all whom it may concern:

Be it known that I, Henry R. Heller, a citizen of the United States, residing at New York city, in the county of Bronx and State of New York, have invented a new, original, and ornamental Design for a Piano, of which the following is a specification, reference being had to the accompanying drawing, forming a part thereof,

The drawing shows a perspective view of a piano embodying my new design.

I claim:

The ornamental design for a piano, as shown.

HENRY R. HELLER,
